By Henry L. Ernst, Atty.

UNITED STATES PATENT OFFICE.

ABRALOM W. SPEAR, OF WILKINSBURG, PENNSYLVANIA.

DESIGN FOR A NUT-LOCK.

SPECIFICATION forming part of Design No. 26,801, dated March 23, 1897.

Application filed December 7, 1896. Serial No. 614,851. Term of patent 7 years.

To all whom it may concern:

Be it known that I, ABSALOM W. SPEAR, a citizen of the United States of America, residing at Wilkinsburg, in the county of Allegheny and State of Pennsylvania, have invented a certain new and original Design for Nut-Locks, of which the following is a specification, reference being had therein to the accompanying drawing.

This invention relates to a new and original design for nut-locks, and in describing the invention in detail reference is had to the accompanying drawing, forming a part of this specification, the view shown being a perspective of my design for a nut-lock.

The leading feature of my design consists

in the washer *a*, circular in its general contour and having inclined undercuts *b b* on each face thereof, the undercuts of one face being inclined in the reverse direction from those of the opposite face, said undercuts being located diametrically opposite each other.

What I claim is—

The design for a nut-lock as shown and described.

In testimony whereof I affix my signature in presence of two witnesses.

ABRALOM W. SPEAR.
